UNITED STATES PATENT OFFICE.

MILES R. B. COWAN, OF WINDSOR, ONTARIO, CANADA, ASSIGNOR, BY MESNE ASSIGNMENTS, OF TWO-THIRDS TO HENRY W. BOOTH, OF SAME PLACE, AND FRANK H. LEAVENWORTH, OF DETROIT, MICHIGAN.

SHIELD AND BLOTTER.

SPECIFICATION forming part of Letters Patent No. 310,257, dated January 6, 1885.

Application filed July 23, 1884. (No model.)

To all whom it may concern:

Be it known that I, MILES R. B. COWAN, of Windsor, in the county of Essex and Province of Ontario, Canada, have invented new and useful Improvements in Shields and Blotters; and I do hereby declare that the following is a full, clear, and exact description thereof, reference being had to the accompanying drawings, which form a part of this specification.

10 This invention relates to certain new and useful improvements in the construction of shields and blotting-pads; and the invention consists in the peculiar construction, arrangement, and combination of parts, as hereinafter more fully described and claimed.

Figure 1 is a view of my improved shield-pad detached; and Fig. 2 shows the same attached to the hand of the wearer, in such manner as to be presented between the palm of his hand and the paper upon which he is writing.

In the accompanying drawings, which form a part of this specification, A represents a bed formed of as many pieces or thicknesses of blotting-paper as may be desired, cut substantially in the form shown, so that the broader portion will entirely prevent the palm of the hand from contact with the paper upon which the writing is being made, while secured to the narrow portion is a flexible band, B, adapted to attach such pad to the wrist of the wearer. The various thicknesses of the pad, the sheets being all coincident in size and shape, need not be secured together in any other way than by means of the eyelet a, or other fastening employed to secure the strap to them.

In writing with this pad upon the wrist the exposed sheet of blotter is employed for blotting the manuscript until its absorbent qualities are apparently exhausted, when it may be torn off and the next one in succession brought into operation.

C represents a piece of kid, leather, or other suitable material coincident in size and shape with the blotting-pads, secured to the flexible strap by the same device which secures the strap to the blotting-pads, which is placed so

that when the whole device is attached to the wrist this piece C rests against the hand and prevents the perspiration thereof from defacing the paper upon which the writer is operating, or injuring the blotting-pads below it.

I am aware that a combined blotting-pad and hand-rest is not new; and I therefore do not claim, broadly, a combined blotting-pad and hand-rest, but limit myself to the exact construction shown, which construction I deem a decided improvement over those heretofore used.

I attach importance to the shape of the pad A, which, it will be seen, is pear-shaped, or substantially so, which affords protection for the hand and fingers, as well as for the wrist, and by having the securing-strap fastened at one end, instead of at the center, as has been the custom, the device will protect the paper from the whole hand and still allow the strap C to encircle the wrist at a point where it will not contract the muscles and cramp the hand.

This blotter is simple, inexpensive, and durable, and the various parts may each and all be readily replaced by new ones when they are worn out, one eyelet serving to secure all the parts together.

What I claim as my invention is—

1. A combined hand-rest and blotter consisting of a pad having an expanded portion conforming to the shape of the hand, and a contracted portion conforming to the shape of the wrist, in combination with an elastic strap attached to said contracted portion to secure the pad to the wrist of the penman, and allow the expanded portion to extend forward and form a rest for the penman's fingers, substantially as shown and described.

2. The combination of the blotting-pad A, shield C, covering said pad on one side, elastic strap B, and the eyelet a, said eyelet securing the various parts together, substantially as herein shown and described.

MILES R. B. COWAN.
